GARMENT VALET RACK

Robert H. Reynolds, Clarksdale, Miss.

Application May 25, 1956, Serial No. 41,662

Term of patent 14 years

(Cl. D33—8)

FIG. 1

FIG. 2

FIG. 3

I claim:

The ornamental design for a garment valet rack, as shown.
